UNITED STATES PATENT OFFICE.

JAMES WHITESIDE, OF NEW YORK, N. Y.

CONVERTIBLE BOAT-PROPELLING APPARATUS.

SPECIFICATION forming part of Letters Patent No. 714,766, dated December 2, 1902.

Application filed January 29, 1902. Serial No. 91,797. (No model.)

To all whom it may concern:

Be it known that I, JAMES WHITESIDE, a subject of the King of Great Britain, and a resident of New York city, county and State 5 of New York, have invented certain new and useful Improvements in Convertible Boat-Propelling Apparatus, of which the following is a specification.

My invention consists of improved means 10 of converting boat-propelling apparatus for use of the boat either in the water or on ice, as hereinafter described, reference being made to the accompanying drawings, in which—

Figure 1 is partly a longitudinal vertical 15 section and partly a side elevation of a boat that may be used in the water with screw propelling apparatus with apparatus applied for propelling it on ice, said apparatus being interchangeable with the apparatus for use in the water. Fig. 2 is a plan view of the same 20 with some parts broken out. Fig. 3 is a detail intended to indicate the application of the same principle to paddle-wheel boats.

A represents a small boat of ordinary construction, such as may have any suitable 25 motor for propelling it by a screw mounted at the stern of the boat on a shaft *b*, having the power of the motor applied in any approved way of common knowledge, which it 30 is unnecessary to show. To adapt such a boat for use on ice with the same power apparatus for propelling it, I provide a sleigh-runner attachment of any approved construction whereon it may be mounted, as on 35 the runners *c*, suitably for carrying the boat. In this example the connection is made by means of posts or knees *d* resting on the runners and at their upper ends attached to the sides of the body of the boat, as at *e*, so 40 as to be readily detachable, with the upturned ends of the runners also attached at *f* to the sides of the bow-quarters and with a cross-bar *g* connected to standards *g'* on the hind ends of the runners, thus utilizing the body 45 of the boat as part of the ice-boat structure; but it is obvious that the body structure of the ice-boat may be a crib or cradle of complete structure independent of the boat and adapted for receiving the boat and properly 50 holding it without any special connection of the two.

A bevel gear-wheel *h* is substituted in the

place of the usual propeller on the propeller-shaft *b*, which gears by another wheel *j* with a transverse shaft *i*, supported in suitable 55 bearings *k*, supported on the runners *c*, and behind this shaft and parallel with it a propelling-shaft *l* is carried in the rear extremities of arms *m*, pivoted at *n* to the hind posts *d* of the runners, or it may be to any attachment 60 to the runners, as the crib or cradle above referred to, if used, and on this shaft *l* one or more spike-wheels or drums *o* are mounted for propelling the runners by engaging the ice and being rotated by suitable 65 connection of said shaft *l* with the shaft *i*, as the belts *p* and pulleys *q r*, or other approved means. The arms *m* being pivoted at their 70 connection with the posts *d* enable the spike-wheels to rise and fall automatically for passing any irregularities in the surface of the ice, such as are often encountered. To prevent clogging of the spikes, clearing-teeth *w* may be attached to bar *g*, said teeth extending 75 into the spaces between the spikes.

In Fig. 3 *t* may be considered a section of the side of a paddle-wheel boat, and *u* a spike-wheel substituted for a paddle-wheel on the usual paddle-wheel shaft *v* to indicate the same principle applied to a paddle-wheel boat. 80

Thus the usefulness of small boats on rivers, lakes, and other bodies of water subject to freezing over in winter may be considerably increased.

What I claim as my invention is—

1. The combination with a boat and power apparatus adapted for propelling it in water, of a runner attachment of detachable application adapted for carrying the boat on ice and a propeller adapted for working on the 90 ice and geared with the water-propeller shaft by a wheel that is interchangeable with and is substituted for the water-propeller directly on the water-propeller shaft, said shaft being the same on which the water-propeller is directly applied.

2. The combination with a boat and power apparatus adapted for propelling it in water, of a runner attachment of detachable application adapted for carrying the boat on ice 100 and a propeller adapted for working on the ice and geared with the water-propeller shaft by a wheel that is interchangeable with and is substituted for the water-propeller directly

on the water-propeller shaft, said shaft being
the same on which the water-propeller is di-
rectly applied, said ice-propeller consisting
of one or more rotatory spiked drums, ver-
5 tically-vibrating arms carrying said spiked
drums at the stern of the boat and suitably
connected with the runner attachment, a coun-
ter-shaft geared with the wheel on the pro-

peller-shaft, and also geared with the spiked
drum-shaft.

Signed at New York city this 17th day of
January, 1902.

JAMES WHITESIDE.
